Patented Mar. 1, 1966

203,937

TOY AUTO RACEWAY

George W. Dunbar, Nashville, Tenn., assignor to Kusan,
Inc., Nashville, Tenn., a corporation of Kentucky

Filed Nov. 5, 1964, Ser. No. 82,493

Term of patent 14 years

(Cl. D34—15)

FIG 2

FIG 3

FIG 4

FIG 5

FIGURE 1 is a top plan view of the toy auto raceway, showing my new design;

FIGURE 2 is an elevational view of one side thereof;

FIGURE 3 is an elevational view of the other side thereof;

FIGURE 4 is an elevational view of one end thereof;

FIGURE 5 is an elevational view of the other end thereof; and

FIGURE 6 is a top plan view of the lower portion thereof which is partially hidden in FIGURE 1.

I claim:

The ornamental design for a toy auto raceway, as shown.
